UNITED STATES PATENT OFFICE

2,603,788

GARMENT

Mable T. Page, Kansas City, Mo.

Application December 2, 1949, Serial No. 130,633

7 Claims. (Cl. 2—106)

1

This invention relates to a garment and more particularly a blouse, the principal objects being to provide an attractive garment of this character having a simple, inexpensive construction and which is adapted to be worn in various forms to present different styles.

Other objects of the invention are to provide a garment suitable for various sized and shaped figures, thereby reducing the stock sizes; to provide a garment construction which requires a minimum of material and substantially no intricate cutting or stitching; to provide a garment with a portion that may be worn as a hood, collar, or as a loose fitting back.

In accomplishing these and other objects of the invention, I have provided improved structure the preferred form of which is illustrated in the accompanying drawings wherein:

Fig. 1 is a perspective view of a garment constructed in accordance with the present invention.

Figs. 2, 3 and 4 illustrate various steps in donning the garment.

Fig. 5 is a perspective view of the garment showing the fastenings thereof and the shape it assumes when the fastening elements are secured together.

Fig. 6 shows a front view of the garment when applied in one manner.

Fig. 7 is a rear view of the garment as applied as shown in Fig. 6.

Fig. 8 is a perspective view of the garment showing the garment applied to expose the midriff of the wearer.

Fig. 9 is a view similar to Fig. 8, but showing the back portion moved into position for forming a hood.

Fig. 10 is a back view of the garment as applied in Fig. 9.

Fig. 11 is a perspective view of a modified form of the garment.

Fig. 12 is a perspective view of the shape that the modified garment assumes when the fastening element or lacing is applied.

Referring more in detail to the drawings:

1 designates a garment embodying the features of the present invention and which is formed of a single strip of material having substantially rectangular shape and folded longitudinally along the center thereof in parallel relation with side edges 2 and 3 as indicated at 4 to provide overlapping portions 5 and 6. The garment may be formed of various materials which may or may not have stretch, however, jerseys and similar stretchy fabrics are very satisfactory. The

edges 2 and 3 opposite the fold 4 may be suitably finished by turning back the edges in the form of hems 7 and attaching the hem 7 by continuous lines of stitching as indicated at 8. The end edges 9—10 and 11—12 of the portions 5 and 6 are folded inwardly and suitably secured together by lines of stitching 13 and 14, this stitching extending from the hems 7 to terminate at a point spaced from the fold 4 to provide arm holes 15 and 16 immediately adjacent the ends of the fold 4 as shown in Fig. 1. The edges of the arm holes may be hemmed and secured by stitching 17 to provide finished edges. One side portion, for example, the side 5 is provided at spaced points from the respective ends of the garment with a plurality of spaced apertures 18 and 19. Located on the opposite portion 6 preferably close to the finished edge or hem 7 thereof, and spaced from the ends of the garment is a hook 20 and an eye 21 respectively to connect the open edges of the garment when the garment is applied by a wearer.

The spacing indicated 22 between the sets of apertures 18 and 19 constitute the waist line 25 and the lengths from the eye 21 to the apertures 18, designated 23, and from the hook 20 to the aperture 19, designated 24, constitute the edges of the neck opening 25 of the garment. The portion, designated 26, between the hook and eye 20 provides the loose fitting back 27, the collar 28, or the hood 29 as shown in Figs. 7, 8 and 9 respectively.

In donning a garment constructed as described the garment is placed across the back so that the arms may be projected through the opening between the side edges 2 and 3 and through the arm hole openings 15 and 16. The edge portion of the side 6 carrying the hook and eye 20 and 21 is extended over the shoulders as shown in Fig. 2 so that the hook 20 and eye 21 may be brought together and engaged at the back of the neck as shown in Fig. 3. In this position the seams formed by the stitching 17 extend from the neck in a downwardly direction toward the under side of the arms. The portions of edge 2, having the apertures 18 and 19, are then brought together in front of the body and secured together by suitable lacing 30 as shown in Fig. 6. If a shorter neck line is required a suitable pin 31 or the like may be used in securing the edges of the neck portion together at a point above the lacing. The portion 26 of the garment between the hook 20 and eye 21 may be left loosely draped as shown in Fig. 7 or the portion 26 may be drawn up around the sides of the

neck and secured to the front of the blouse above the lacing by suitable pins 32 and 33 as shown in Fig. 8 to provide the collar 28. If desired, the loose fitting portion of the garment may be drawn upwardly over the head to form the hood 29 as shown in Figs. 9 and 10.

The form of the invention shown in Figs. 11 and 12 is substantially the same as that illustrated in Figs. 1 to 10 inclusive with the exception that a lining strip 34 is secured over the inner face of one side 35 of the garment, as shown in Fig. 11, then when the garment is applied the strip lining which is left unattached along the lower edge 36 may be drawn outwardly around the neck to provide a collar. If desired, the lining may be a different color or fabric so as to give a collar effect having the color different than the color of the garment.

While I have particularly described the invention in connection with a blouse, it is obvious that it is adapted to various forms of garments and may be used in various dress combinations.

From the foregoing, it is obvious that I have provided an attractive garment having a simple and inexpensive construction and which is adapted to be worn in various forms to present different styles. It is also obvious that the garment may be formed of a minimum amount of material and no complicated cutting or stitching is required in producing the garment. It is also obvious that the garment may be adapted to various sized and shaped figures so that no more than three sizes need be stocked to supply the trade demand.

What I claim and desire to secure by Letters Patent is:

1. A garment of the character described including a rectangular strip of material having a longitudinal fold to provide overlapping portions having finished edges along the sides thereof opposite the fold and having the ends secured together from said edges to points terminating short of the fold for providing arm openings, fastening devices on the edge of one of said portions, and fastening means on the edge of the other portion and spaced from said ends.

2. A garment of the character described including coextensive portions secured together at ends and one side with opposite side edges of said portions unattached, said portions having arm holes at the ends and fastening means spaced along the free edge of one of said portions and adapted to be connected together at the back of a wearer of the garment when the arms are extended between said free edges of said portions and through the arm holes, and means on spaced apart portions of the free edge of the other portion for connecting said spaced portions together across the front of the wearer.

3. A garment of the character described including coextensive portions secured together at ends and one side with opposite side edges of said portions unattached, said portions having arm holes at the ends and fastening means spaced along the free edge of one of said portions and adapted to be connected together at the back of a wearer of the garment when the

arms are extended between said free edges of said portions and through the arm holes, and means on spaced apart portions of the free edge of the other portion for connecting said spaced apart portions together across the front of the wearer, the free edges of said one portion between the fastening means at the back being adapted to drape at the back of the wearer.

4. A garment of the character described including coextensive portions secured together at ends and one side with opposite side edges of said portions unattached, said portions having arm holes at the ends and fastening means spaced along the free edge of one of said portions and adapted to be connected together at the back of a wearer of the garment when the arms are extended between said free edges of said portions and through the arm holes, and means on spaced apart portions of the free edge of the other portion for connecting said spaced apart portions together across the front of the wearer, said one portion between the fastening means at the back being adapted to form a hood adapted to be pulled over the head of the wearer.

5. A garment of the character described including coextensive portions secured together at ends and one side with opposite side edges of said portions unattached, said portions having arm holes at the ends and fastening means spaced along the free edge of one of said portions and adapted to be connected together at the back of a wearer of the garment when the arms are extended between said free edges of said portions and through the arm holes, and means on spaced apart portions of the free edge of the other portion for connecting said spaced apart portions together across the front of the wearer, said one portion between the fastening means at the back being adapted to form a collar.

6. A garment of the character described including coextensive rectangular portions, connected together at opposite ends and along one side and having free edges at the opposite side, said ends having arm holes at the connected side, and a lining strip secured to the inner side of one of said portions along the free edge thereof to provide a collar.

7. A garment of the character described including a rectangular strip of material folded along the center to provide overlying portions, stitching securing opposite end edges of the portions together, said stitching terminating short of the fold to provide arm holes adjacent the fold, and a lining strip secured to the inner side of one of said portions at the side opposite said fold.
